UNITED STATES PATENT OFFICE.

POVL T. LINDHARD, OF BROOKLYN, NEW YORK, ASSIGNOR TO F. L. SMITH & CO., OF NEW YORK, N. Y., A CORPORATION OF NEW JERSEY.

GRINDING MILL, ETC.

Application filed July 20, 1921. Serial No. 486,093.

To all whom it may concern:

Be it known that I, POVL T. LINDHARD, a citizen of the United States, residing in the borough of Brooklyn of the city of New York, in the State of New York, have invented certain new and useful Improvements in Grinding Mills, Etc., of which the following is a specification, reference being had to the accompanying drawings, forming a part hereof.

This invention has been developed with particular reference to the improvement of the operation of grinding mills, in which the material operated upon is subjected to the action of balls or other grinding bodies employed in successive chambers within a shell or drum which is rotated on a substantially horizontal axis, and in which the material operated upon by the grinding bodies is also subjected, in its passage from one chamber to another, to a screening operation, the material rejected by the screen being returned to the preceding chamber for further reduction, while the screened material passes on to the succeeding chamber wherein it is further reduced by other grinding bodies of different characteristics. It will nevertheless be understood that the improvements herein described, although designed for use in such a mill and for joint operation, are capable of use independently and in mills or apparatus of a different character. Thus, while one part of the invention is designed to provide a relatively great screening surface within a comparatively restricted space between two successive chambers of a grinding mill, it will be obvious that the improvements in the screening devices are capable of use independently of any grinding devices, as when the sole or chief purpose is the screening or separation of certain substances. So also the other main part of the invention, which relates to the changing of the volumetric capacities of successive grinding chambers, so as to suit the requirements of different materials and different conditions of operation, although designed primarily for the improvement of such a mill as that illustrated and of which the improved screening devices or separators form a part, is nevertheless capable of application in connection with other screening devices or separators and in mills or apparatus of a different character. The invention will be explained more fully hereinafter with reference to the

accompanying drawing in which convenient and practical embodiments are illustrated and in which—

Figure 1 is a view in longitudinal, central section of a grinding mill of the particular type known in the art as a combination tube mill, in which the features of the invention are embodied.

Figure 2 is a section on the plane indicated by the broken line 2—2 of Figure 1, looking in the direction of the arrows.

Figure 3 is a detail view in longitudinal section on a larger scale showing particularly the means for securing a partition in adjusted position.

Figure 4 is a detail view in section on the plane indicated by the broken line 4—4 of Figure 3, looking in the direction of the arrows.

In the structure shown in the drawing, which may be of usual or preferred construction except as hereinafter indicated, the generally cylindrical shell *a*, having a lining *b*, is provided at one end with an inlet head *c* and at the other end with a discharge head *d*, and is mounted to rotate on a substantially horizontal axis. In this mill are shown two successive grinding chambers, a primary grinding chamber *e* and a secondary grinding chamber *f* separated, in this instance by an intermediate screening or separating compartment *g*, which is itself capable of adjustment, either as to its own length or in position as a whole or in part, for the purpose of varying the relative volumetric capacities of the chambers *e* and *f*, as may be required by the conditions of operation of the mill or apparatus. Such variation in the relative volumetric capacities of the chambers *e* and *f* might be effected without the employment of a screening or separating compartment, such as that illustrated, as by the employment of a partition which, in the construction shown, forms one end of the separating compartment and is itself adjustable or movable longitudinally within the shell *a*.

As shown such adjustable partition comprises a plate *h* which may be provided near its periphery with apertures *h'*, through which the partially reduced material may pass from one side to the other of the partition while the grinding bodies and the coarser material are retained in the primary grinding chamber. The corresponding partition plate *h*, at the other end of the sep-

rating chamber, is shown as having marginal openings as at h^3 , through which the material passes. Secured to each partition plate, h , h^2 , is shown the usual device i by which the material which has passed the partition plate and has been lifted in the rotation of the drum, is directed through the central opening of a co-operating partition plate k . The latter is provided with radial ribs k' , the extremities k^2 of which, spaced from the lining b of the shell, are inclined, as shown clearly in Figure 3, to form wedge surfaces. Arranged for cooperation with each radial rib k' is a wedge block l which at one side is formed with a convex shoe l' to conform to the inner surface of the lining b of the shell and at its other edge is inclined and grooved, as at l^2 , to co-operate with the wedge surface k^2 of the rib. By means of a bolt m passed loosely through the wedge block and through the plate k , the wedge block may be drawn toward the plate k and thereby be forced outwardly to press firmly against the lining b of the shell a and so secure the partition plate k in adjusted position. The plate h is loosely secured to the wedge blocks l so as to be held in position thereby, while permitting the necessary radial movement of the wedge blocks. By the means thus described, the partition formed of the plates h , k or the partition formed of the plates h^2 , k , or both of them, can be released from the shell and its lining, shifted longitudinally to permit such variation as may be desired in the volumetric capacities of the chambers e and f and, in the structure shown, the length of the separating chamber, and can then be secured firmly in adjusted position.

In the structure shown there are two partitions, one at each end of the separating chamber g . For the purpose of providing within a comparatively, short space a great separating or screening surface, the separating compartment c comprises a series of intercommunicating separators n which are supported by the partition plates k and h^2 and by each other, each separator consisting of an annular cage arranged transversely in the shell and having annular side walls n' , perforated to form screens, and a peripheral wall n^2 , which may be imperforate, and, in the construction shown, is spaced from the lining of the shell. At the inner edge of the annular side walls is an opening n^3 to admit into the screening space the material under treatment and, in the revolution of the shell, to discharge for further treatment the coarse material which does not pass through the screens. As shown, each side wall is spaced from the adjacent side wall with which it forms a pair, or from the adjacent partition plate, whereby each perforated wall is unobstructed and there is formed a space through which the screened material may pass from the separators, in a general radial

direction, into the space between the separators and the shell with its lining, which, in the structure shown, forms a means to receive the screened material from the separators. In this space there are also shown conveyor ribs o by which, in the rotation of the shell, the screened material is caused to travel onward until it is discharged into the succeeding chamber f . It will be noted that the perforated side walls n' are annular only, having large central openings, so that together they form intercommunicating separators from one to the other of which, throughout the series, the material which has not been reduced to such a degree of fineness as to pass through the perforated annular walls, may pass on until it is so reduced. These side walls are not extended entirely across the separating chamber, for if so extended they would form between them separate grinding compartments and would prevent the accomplishment of the main purpose of this invention, namely, to provide great screen surface within a limited space, the accomplishment of this purpose being possible only with annular transverse screens with provision for the passage of coarse material over each screen into the next separator compartment. As indicated in Figures 1 and 2, the separator compartments may each be formed for convenience in circumferential sections and the several separators be bolted to each other and to the adjacent partition plates. The arrangement of the screens transversely with respect to the axis of the shell with spaces at the outer screen faces through which the screened material may be discharged, makes it possible to provide great screen surface within a limited space and so enables the production to be increased greatly as compared with screening devices heretofore employed.

It will be obvious not only that the area of screening surface can be varied at will by adding or removing separator units between the movable end walls or partition plates, but that the relative volumetric capacities of the chambers e and f can be varied at will, either by shifting the separator compartment as a whole toward one end or the other or by adding or removing a separator unit at one end or the other of the separator compartment. In this manner the maximum efficiency of the apparatus can be attained with materials and grinding bodies of different characteristics.

It will be understood that various changes in details of construction and arrangement can be made to suit different conditions of use and that, except as pointed out in the claims, the invention is not restricted to the precise construction shown and described herein.

I claim as my invention:

1. A rotary separator having a peripheral

wall and two annular perforated side walls having an opening between their inner edges to admit into the screening space the material under treatment and to discharge the coarse material, the faces of both side walls being unobstructed so as to permit the screened material to pass outward through both side walls.

2. A rotary separator comprising a series 10 of intercommunicating separator units, each separator unit having a peripheral wall and an annular perforated side wall with an opening at its inner edge to admit into the screening space the material under treatment and to discharge the coarse material, 15 the faces of the several side walls being unobstructed so as to permit the passage of the material through said side walls.

3. A rotary separator comprising a series 20 of transverse annular screens, said screens being arranged in series to form intercommunicating separator compartments spaced from each other to permit the screened material to pass from adjacent compartments 25 into the space between, and means to receive the screened material from such intermediate spaces.

4. A rotary separator comprising a series 30 of transverse annular screens, said screens being arranged in series to form intercommunicating separator compartments spaced from each other to permit the screened material to pass from adjacent compartments 35 into the space between and means to receive the screened material from such intermediate spaces and convey it in a longitudinal direction.

5. The combination of a rotating shell, and a series of annular separator units supported

therein and spaced interiorly from the shell 40 to form a chamber into which the screened material passes from the separator units, each separator unit having a peripheral wall and perforated side walls, the perforated faces being unobstructed so as to permit the 45 passage of the screened material.

6. The combination of a rotating shell, and a series of annular separator units supported 50 therein and spaced interiorly from the shell to form a chamber into which the screened material passes from the separator units, each separator unit having a peripheral wall and perforated side walls, the perforated faces being unobstructed so as to permit the 55 passage of the screened material and conveyor ribs in the space between the separator units and the shell.

7. The combination of a shell, a transverse partition plate provided with longitudinally movable wedge surfaces, wedge blocks arranged to co-operate with the wedge surfaces and to bear against the shell, and means to move the wedge blocks longitudinally in the shell.

8. The combination of a shell, a transverse 65 partition plate having radial ribs forming wedge surfaces at their extremities, wedge blocks to co-operate with the wedge surfaces and to bear against the interior of the shell, and bolts to draw the wedge blocks on the 70 wedge surfaces toward the partition plate.

9. The combination of a rotating shell, a separator composed of a series of independent, detachable separator units, and means to secure the separator within the shell. 75

This specification signed this 15th day of July A. D. 1921.

POVL T. LINDHARD.
